UNITED STATES PATENT OFFICE.

FRANK LESLIE WHARTENBY, OF GALION, OHIO.

LOCK FOR THE CLOSURES OF BURIAL-VAULTS.

1,288,455.

Specification of Letters Patent. Patented Dec. 17, 1918.

Application filed March 5, 1918. Serial No. 220,569.

To all whom it may concern:

Be it known that I, FRANK LESLIE WHARTENBY, a citizen of the United States, residing at Galion, in the county of Crawford 5 and State of Ohio have invented certain new and useful Improvements in Locks for the Closures of Burial-Vaults, of which the following is a specification.

This invention relates to improvements in 10 burial vaults and more particularly to an improved locking and binding device for the closures of such vaults. The primary object of the present invention is to provide a combined locking and binding device which 15 will serve to secure the closure for the vault in position in such manner as to render the vault air and water-tight and also burglar proof.

Various devices have heretofore been employed for the purpose of securing in place 20 the closures of metallic burial vaults and a well known type of such devices includes locking bolt members which are designed to be simultaneously shot into place through 25 the rotation of a spindle by the application to the spindle of a wrench or the like applied exteriorly of the closure. While such devices are generally adapted to securely lock the closure against removal, practically 30 all of such devices possess the disadvantage of being incapable of locking or binding the closure in place in a manner to render the vault absolutely air and water-tight. As 35 stated the locking bolt members are designed

ordinarily to be shot into place through the rotation of a spindle by the application to 40 said spindle of a wrench or similar tool, and the locking bolt members are provided with elements which engage keepers upon the 45 vault closure and seat behind a flange located immediately inwardly of the receiving opening of the vault. However, even with the application of considerable force in the rotation of the spindle to shoot the locking bolt members into locking position, it has 50 been found that the engagement of these members with their respective keepers cannot serve alone to so tightly draw the closure into position within the receiving opening as to cause its edges to press against the 55 packing usually provided upon the flange above mentioned, in a manner to absolutely seal the vault at the said opening. The present invention, therefore, has as one of its primary aims to provide, in a vault closure locking device of this general type, means

whereby the spindle may be so adjusted, aside from its rotary adjustment, as to cause the locking members to exert leverage between the flange above-mentioned and the 60 keepers so that after the locking bolt members have been shot into engagement with their keepers, this further adjustment of the spindle may be accomplished so as to cause 65 the lever action of the locking members against the keepers as above stated and thereby pull inwardly with great force upon the keepers to cause the edges of the inner face of the vault closure to exert great compressive force against the packing strip 70 upon the seating flange which surrounds the receiving opening in the vault. Thus not only is the closure securely locked in position, but it is forcibly drawn inwardly so 75 as to absolutely seal the vault.

The invention also aims, as above stated, to so construct the locking device that it will serve to positively preclude removal of the closure after having been once locked in place, thereby rendering the vault burglar- 80 proof.

Another aim of the invention is to provide a simple and yet highly efficient means for holding and guiding the locking bolt members in their assembled relation with the 85 spindle and vault closure so as to permit of both the sliding movement of the bolt members into locking position and the canting thereof when they are adjusted to exert 90 leverage as above mentioned.

In the accompanying drawings:

Figure 1 is a view in elevation of the device embodying the present invention, the vault being shown in vertical transverse section and the locking bolt members being 95 shown in locking position;

Fig. 2 is a vertical sectional view taken substantially on the line 2-2 of Fig. 1 and illustrating the locking bolt members shot into engagement with their keepers but also 100 illustrating the parts in the positions which they will occupy prior to the adjustment of the spindle to cause the said bolt members to exert leverage against their keepers.

Fig. 3 is a detail horizontal sectional view 105 taken substantially on the line 3-3 of Fig. 2;

Fig. 4 is a view similar to Fig. 3 but illustrating the spindle adjusted so as to cause the bolt members to exert leverage against 110 their keepers.

The vault body is indicated in general by

the numeral 1 and may be of any desired construction, and at one end the said body is provided with a receiving opening 2 designed to be closed by means of a closure 3 preferably in the nature of a plate of the required size and shape to fit within the said opening. The walls of the vault body are provided or formed upon their inner surfaces immediately inwardly of the opening 2 with a continuous inwardly projecting seating flange 4 against the outer face of which is disposed a packing strip or gasket 5 of any suitable material such, for example, as rubber or leather. While the device of the present invention is herein illustrated and described as applied to a closure located at one end of the vault body, it will be understood that the device of the invention may be employed in locking in place a closure fitted within an opening in the top of the vault or in either side thereof. The flange 4 is formed at suitable intervals with openings or slots 6 which receive the keeper elements upon the closure 3 when the closure is fitted into place with its margin at its inner face resting against the packing strip 5, these keeper elements being indicated by the numeral 7 and being preferably of the form shown in the drawings and each including spaced side portions riveted or otherwise secured to the closure 3, and a connecting portion which, when the closure has been fitted into place, occupies a position spaced inwardly from the inner face of the flange 4, as clearly shown in Fig. 2 of the drawings. As the keepers 7 are arranged in series extending along the two side walls, the bottom, and the top of the closure, four of the locking bolt members 8, 9, 10 and 11, and each of the said members comprises a head 12 of any suitable conformation, the heads, however, being preferably somewhat frame-like so as to economize in material and yet be sufficiently strong to perform their locking function. The head of the bolt member 8 is designed to be moved toward and away from the upper side of the receiving opening of the vault; the head of the member 9 is designed to be moved toward and away from the lower side of the said opening; and, the heads of the members 10 and 11 are designed to be moved toward and away from the opposite sides of the opening and each head is provided at its outer edge or side with a number of locking fingers indicated by the numeral 13 which fingers are designed to engage with the respective ones of the keepers 7, as clearly shown in Figs. 1 and 2 of the drawings, the fingers 13 in their locking engagement with the keepers, seating between the connecting portions of the keepers and the

inner face of the flange 4 as best illustrated in Fig. 2. In order that the fingers may have wedging engagement between these parts and thus serve, as the bolt members are shot into locking position, to exert a pull inwardly upon the keepers and, consequently, upon the closure 3, each finger has its outwardly presented face, or in other words, that face which is presented toward the flange 4, beveled as indicated by the numeral 14. However, the fingers may be of some other suitable wedge formation if found desirable. In the present instance as the locking members are shot outwardly through the rotation of the spindle, as will be presently described, the inclined faces of the fingers will ride against the inner face of the flange 4 and, consequently, the opposite faces of the fingers will be caused to bear more firmly against the connecting portions of the keeper members as the said bolt members are forced outwardly. In order to guide the bolt members in their sliding movements and also to assist in holding the members in proper position upon the inner face of the closure 3, short posts or bosses 15 are formed or secured upon the said inner face of the closure plate 3, and guiding screws 16 are threaded into the inner ends of these bolts or bosses and extend through slots 17 formed in suitable portions of the heads of the several bolt members 8, 9, 10 and 11. Preferably two parallel slots 17 are formed in the head of each of the bolt members so as to more effectually guide the said members as they are slid into and out of locking position. It will be observed, however, by reference to Figs. 2, 3 and 4 of the drawings that the portions of the screws 16 which are engaged by the walls of the slots 17, are of a length greater than the thickness of the heads of the locking bolt members in which the slots are formed so that the said locking bolt members may have canting movement in addition to the sliding movement given them through rotation of the spindle heretofore referred to. The spindle heretofore referred to is indicated by the numeral 18 and the said spindle is rotatably and longitudinally slidably mounted in an opening 19 formed through the closure 3. Substantially at its inner end, the spindle has formed or fixed thereon a gear 20 which is relatively broad, and the heads of the bolt member 8, 9, 10 and 11 are provided respectively with shanks 21, 22, 23 and 24 which extend from the inner ends of the said heads, the shanks 21 and 22 extending vertically at opposite sides of the gear 20 and the shanks 24 and 23 extending respectively above and below said gear. The several shanks are formed each with a rack 25 and the several racks mesh with the gear 20 in the manner clearly shown in Fig. 1 of the drawings. In order to hold

the shanks 23 and 24 in position with the racks meshing with the gear 20, a guide yoke is provided and the said yoke is preferably formed from a plate 26 having its 5 ends turned at right angles as at 27, the plate being disposed against the inwardly presented sides of the said shanks 23 and 24 with its ends extending respectively below and above the lower and upper edges 10 of the shanks 23 and 24. The plate is formed between its ends with an opening 28 receiving the end of the spindle 18 inwardly of the gear 20, and a screw or the like 29 is fitted into the end of the spindle and has 15 interposed between it and the said plate one or more washers 30, the plate being in this manner held assembled with the spindle and in position to guide the shanks 23 and 24. A similar plate 31 is also fitted onto the 20 spindle 18 between the gear 20 and the closure 3 and against the adjacent faces of the shanks 21 and 22 and this plate has angularly bent ends 32 which engage the outwardly presented lateral edges of the said 25 shanks and serve to guide the shanks in the manner above stated with regard to the plate 26. For a purpose to be presently explained, a relatively heavy bowed leaf spring 33 is provided between its ends with an 30 opening 34 which adapts it to be fitted upon the spindle 18, and the intermediate portion of this spring bears against the plate 31 and serves to hold the same in guiding position with relation to the shanks 21 35 and 22, and the ends of the said spring bear against the inner face of the closure 3. In order to limit the inward movement of the spindle 18 under the influence of the spring 33, the spindle is increased in diameter ad- 40 jacent its outer end and exteriorly of the closure 3 thus forming a shoulder 35 which bears against the outer face of the closure 3 for the purpose stated. The enlarged portion of the spindle is threaded as indicated 45 by the numeral 36 and the outer end of the spindle is of polygonal form for the application of a suitable wrench, as indicated by the numeral 37. It will now be apparent that normally the spring 33 holds the spindle 18 moved inwardly through the opening 19 with the shoulder 35 bearing against the outer face of the closure 3 but that the spring 33 may yield to permit of longitudinal sliding movement of the spindle 18 in an out- 50 ward direction through the said opening. The wrench employed in connection with the locking device is indicated in general by the numeral 38 and the same is provided at one end with a head 39 having a poly- 55 gonal opening 40 to fit the polygonal end 37 of the spindle 18, and the said head is provided inwardly of the opening 40 with a larger polygonal socket 41 which is designed to receive a polygonal head 42 formed at 60 the outer closed end of a cap 43 which is in-

teriorly threaded as indicated by the numeral 44 to engage the threads 36 upon the spindle 18.

Normally, the spindle 18 is rotated to such position that the bolt members will be 70 retracted as shown in Fig. 3 of the drawings and when the bolt members are in this position the closure 3 may be fitted into place in the receiving end of the vault and against the packing strip 5 upon the flange 75 4 and with the keeper elements 7 projecting through the slots 6 in the said flange, the outer ends of the fingers 13 at such time occupying such a position as to clear the inner edge of the flange 4, as shown in the 80 said Fig. 3. After the closure has been fitted into place and it is desired to permanently lock the same, the handle of the wrench 38, which handle is indicated by the numeral 45, is grasped and the wrench is 85 applied to the outer end of the spindle, the polygonal outer end 37 of the said spindle fitted within the opening 40 in the head of the wrench. The wrench is then rotated so as to rotate the spindle 18 and cause the gear 90 95 20 to force all of the locking bolt members in an outward direction. As the bolt members are so moved, the beveled faces of their fingers 13 will ride against the inner edge of the flange 4, thus drawing inwardly 95 against the closure 3, and these fingers will finally engage between the connecting portions of the keeper elements 7 and the said flange 4. This will, of course, serve to securely lock the closure in place, but as heretofore stated it is desirable that means be provided for securely binding the inner face of the closure at its margin against the packing strip 5, and in order that this may be accomplished the wrench 38 is disengaged 100 105 from the spindle and the cap 43 is threaded onto the portion 36 of the spindle until its inner end bears against the outer face of the closure 3. By reference to Fig. 4 of the drawings it will be observed that the threaded socket of the cap is of a length considerably greater than the length of the threaded portion 36 of the spindle. The wrench is then applied to the polygonal head 42 of the cap, the said head being received within the polygonal socket 41 in the head of the wrench, and the wrench is rotated to impart corresponding movement to the cap 43. As the cap is thus turned, the threads therein coacting with the threads 36 upon the spindle 18, will cause the spindle 18 to be slowly and yet positively adjusted longitudinally outwardly through the opening 19 against the tension of the 110 115 spring 33, and as the spindle is moved in this manner, the inner ends of the locking bolt members will be moved inwardly toward the closure 3 and the fingers 13, near their points of juncture with the heads of the respective bolt members, will fulcrum 120 125 130

upon the inner face of the flange 4 at the edge thereof and thus leverage will be exerted by the inwardly presented faces of the fingers against the connecting portions 5 of the keeper elements. Thus as the cap 43 is adjusted, great leverage will be exerted against the keeper elements to draw the closure firmly into place against the packing strip 5 thus effectually sealing the vault 10 in an air and water-tight manner.

In order to prevent the bolt members being retracted after having been once shot into engagement with their keepers, and thus render the vault burglar proof, it is 15 preferable that locking members be provided for coaction with the said bolt members and each of these locking members comprises a resilient shank 46 riveted or otherwise secured to the inner face of the closure 20 3 and yieldably sprung inwardly toward its free end from the said inner face of the closure. Upon each shank there is provided or formed a head 47 having an inclined inwardly presented face, and an abrupt shoulder 48. The locking members above described are located opposite the heads of the bolt members 10 and 11 and each of these heads is formed with an opening 49, one wall 50 of which constitutes a shoulder 25 which is to seat behind the shoulder 48 of the respective locking members after the heads have passed over the inclined faces 47 of the said locking members and their fingers have become engaged in the keeper 30 elements 7.

Having thus described the invention, what is claimed as new is:

1. The combination with a burial vault having a receiving opening, of a closure for the said opening, the vault being provided 40 interiorly with a seating flange for the edges of the closure and the said closure being provided with a keeper element arranged to extend through the flange when the closure 45 is in position within the receiving opening, of locking and binding means for the closure including a bolt member having a locking element for engagement between the said flange and the said keeper element, the bolt 50 member being slidably mounted upon the closure and movable into and out of locking position, a rotatable spindle, operative connection between the spindle and the said bolt member for actuating the latter when 55 the spindle is rotated, and means arranged for coaction with the spindle and closure and adjustable to move the spindle longitudinally outwardly through the closure whereby to cant the bolt member and to 60 cause the locking element to exert leverage from the said flange against the keeper element.

2. The combination with a burial vault having a receiving opening, of a closure for 65 the said opening, the vault being provided

interiorly with a seating flange for the edges of the closure and the said closure being provided with a keeper element arranged to extend through the flange when the closure is in position within the receiving opening, 70 of locking and binding means for the closure including a bolt member having a locking element for engagement between the said flange and the said keeper element, the bolt member being slidably mounted upon the 75 closure and movable into and out of locking position, a rotatable spindle, operative connection between the spindle and the said bolt member for actuating the latter when the spindle is rotated, the spindle having a radially enlarged threaded portion located exteriorly of the closure, and an element having 80 threads engaging the threads upon the spindle and bearing against the said closure and designed when rotated to adjust the 85 spindle longitudinally outwardly through the closure to cant the bolt member and cause its locking element to exert leverage from the said flange against the keeper element. 90

3. The combination with a burial vault having a receiving opening, of a closure for the said opening, the vault being provided interiorly with a seating flange for the edges of the closure and the said closure being provided with a keeper element arranged to extend through the flange when the closure is in position within the receiving opening, of locking and binding means for the closure including a bolt member having a 100 locking element for engagement between the said flange and the said keeper element, the bolt member being slidably mounted upon the closure and movable into and out of locking position, a rotatable spindle, operative connection between the spindle and the said bolt member for actuating the latter when the spindle is rotated, the spindle being 105 slidably through the closure, means located inwardly of the closure yieldably holding the spindle against outward sliding movement through the closure, and means for adjusting the spindle outwardly through the closure to cant the bolt member and cause its locking element to exert leverage 110 between the said flange and the keeper element. 115

4. The combination with a burial vault having a receiving opening, of a closure for the said opening, the vault being provided interiorly with a seating flange for the edges of the closure and the said closure being provided with a keeper element arranged to extend through the flange when the closure is in position within the receiving opening, of 120 locking and binding means for the closure including a bolt member having a locking element for engagement between the said flange and the said keeper element, the bolt member being slidably mounted upon the 125 closure. 130

- closure and movable into and out of locking position, a spindle rotatably and longitudinally slidably mounted through the closure, operative connection between the spindle and 5 the bolt member for actuating the latter when the spindle is rotated, a spring coacting with the spindle and bearing against the closure and yieldably holding the spindle against movement outwardly through the 10 closure, and means arranged for coaction with the closure and operable to draw the spindle outwardly through the closure against the tension of the said spring whereby to cant the bolt member and cause its 15 locking element to exert leverage between the said flange and the keeper element.
5. The combination with a burial vault having a receiving opening and a seating flange adjacent the opening, of a closure 20 adapted to seat against said flange, keepers on the closure to project through said flange, bolt members mounted on the closure for
- sliding and rocking movement, locking fingers on the bolt members to engage between the flange and the keepers, a spindle rotatably and slidably mounted in the closure, a gear on the inner end of the spindle, shanks extending inwardly from the bolt members and passing on opposite sides of said gear, 25 racks on the inner edges of the shank meshing with the gear, guide plates hung on the spindle at the ends of the gear and passing across the shank and engaging the outer edges of the same, a bowed spring acting at its center against the gear and at its edge 30 against the closure, a screw fixed upon the outer end of the spindle and abutting the closure to limit the inward movement of the spindle, means for rotating the spindle, and means to act on the screw to effect sliding movement of the spindle. 35
- In testimony whereof I affix my signature.
